UNITED STATES PATENT OFFICE.

LEVI K. FULLER, OF BRATTLEBOROUGH, VERMONT, AND ALBERT WAGNER,
OF NEW YORK, N. Y.; SAID WAGNER ASSIGNOR TO SAID FULLER.

DESIGN FOR A SEWING-MACHINE BED-PLATE AND ARM.

SPECIFICATION forming part of Design No. 15,171, dated July 29, 1884.

Application filed May 10, 1884. Term of patent 14 years.

To all whom it may concern:

Be it known that we, LEVI K. FULLER, of Brattleborough, Windham county, Vermont, and ALBERT WAGNER, of the city, county, and State of New York, citizens of the United States, have invented a new and useful Design for a Sewing-Machine Bed-Plate and Arm, of which the following is a specification, reference being had therein to the accompanying drawings.

In the drawings, Figure 1 is a side elevation of our newly designed sewing-machine bed-plate and arm. Fig. 2 is a top plan of the same with the vertical portion of the arm in section on line 2 2, Fig. 1. Fig. 3 is a bottom plan of the bed-plate. Fig. 4 is a cross-section of the arm on line 4 4, Fig. 1. Fig. 5 is a cross-section of the bed-plate on line 5 5, Fig. 2. Fig. 6 is a cross-section of a modified form of our bed-plate.

Our bed-plate A has an approximately square rear portion, *a*, on which the base of the bracket-arm rests, and a wider front portion, *b*, the sides of which are parallel, while the front end thereof is gently curved. The sides of the bed-plate, between the front and rear portions, are provided with parallel recesses or notches *d*, which render the central portion, *e*, of the bed-plate very much narrower than the front portion, *b*, and slightly narrower than the rear portion, *a*. The outer corners, *f*, of the bed-plate and also the rear corners, *g*, of the front portion, *b*, have a double or indented curve, while the side recesses terminate at their rear ends with a single curve, *h*. Extending entirely around the outer edge of the bed-plate on its upper side is a rounded molding, *i*. Instead of having this rounded molding, the edge of the bed-plate might be beveled, as shown in Fig. 6, without varying the other characteristic features thereof. On the under side of the bed-plate is an endless rib, *j*, the form of which is clearly shown in Fig. 2.

The arm B consists of a standard, *k*, and an overhanging horizontal portion, *l*, both of these parts being approximately square in cross-section. At the base of the standard *k* is a rounded molding, *m*, above which is a short vertical rectangular portion, *n*. Above

the vertical portion *n* the standard diminishes in size upward on all sides for a short distance, and then again grows larger, the line of contraction and expansion being a concave curve which on the inside of the standard emerges with the curved outline of the lower side of the overhanging horizontal portion *l* of the arm. The outline of the upper side of the portion *l* is a gentle convex curve, and the said portion *l* diminishes in size toward its forward end, enlarging again by steep concave curves adjacent to the fixed part of the needle housing or head *o*, the rear side of which is joined with the forward end of the arm by rounded moldings *p*. Around the outer faces of the arm *B*, beginning just above the vertical portion *n* of the standard, and running thence to the head *o*, are small beads, *r*, between which on each side of the arm is a panel, *s*, convex in cross-section, as shown in Figs. 2 and 4.

We claim—

1. The design for a sewing-machine bed-plate, consisting of rear and front portions, *a* and *b*, having parallel sides, the former being of lesser width than the latter, and a central portion, *e*, of lesser width than said rear portion, said bed-plate being provided with a bracket-arm, as set forth.

2. The design for a sewing-machine bed-plate having a bracket-arm consisting of rear and front portions, *a* and *b*, the former of lesser width than the latter, and a central portion, *e*, of lesser width than said rear portion, said bed-plate having a rounded molding, *i*, around its edge, substantially as set forth.

3. The design consisting of a sewing-machine bed-plate having a bracket-arm, and formed with double rounded or indented outer corners, *f*, and parallel recesses *d*, terminating at their front and rear ends with double and single curves at *g* and *h*, respectively, as set forth.

4. The design for a sewing-machine arm mounted on a bed plate, consisting of the standard *k*, approximately square in cross-section, with a rounded molding, *m*, at its base, surmounted by a vertical rectangular portion, *n*, above which latter the standard curves inwardly and then outwardly, and the over-

hanging portion *l*, approximately square in cross-section and formed in its upper side with a convex curve, substantially as set forth.

5. The design for a sewing-machine arm, of the shape shown, mounted in a bed-plate, consisting of vertical and horizontal portions *k* and *l*, the latter having a head, *o*, which is joined with said horizontal portion by rounded moldings *p*, substantially as set forth.

10. 6. The design consisting of a sewing-machine arm mounted on a bed-plate, and provided on the outer sides of its vertical and horizontal portions with continuous rounded beads *r*, between which, on each side of said arm, is formed a continuous convex panel, *s*, substantially as set forth.

15. 7. The design consisting of a sewing-ma-

chine arm mounted on a bed-plate and having the configuration substantially as set forth.

8. The design consisting of a sewing-ma- 20
chine bed-plate combined with a sewing-ma-
chine arm, both having the configuration sub-
stantially as shown and described.

In testimony whereof we affix our signatures in presence of two witnesses.

Corrections in Design Letters Patent No. 15,171.

It is hereby certified that in Letters Patent No. 15,171, granted July 29, 1884, upon the application of Levi K. Fuller, of Brattleborough, Vermont, and Albert Wagner, of New York, New York, for a "Design for a Sewing Machine Bed-Plate and Arm," an error appears requiring the following correction, viz: In line 58, page 1, of the printed specification, the word "emerges" should read *merges*; and that the Letters Patent should be read with this correction therein to make it conform to the record of the case in the Patent Office.

Signed, countersigned, and sealed this 5th day of August, A. D. 1884.

hanging portion *l*, approximately square in cross-section and formed in its upper side with a convex curve, substantially as set forth.

5. The design for a sewing-machine arm, of the shape shown, mounted in a bed-plate, consisting of vertical and horizontal portions *k* and *l*, the latter having a head, *o*, which is joined with said horizontal portion by rounded moldings *p*, substantially as set forth.

10. 6. The design consisting of a sewing-machine arm mounted on a bed-plate, and provided on the outer sides of its vertical and horizontal portions with continuous rounded beads *r*, between which, on each side of said arm, is formed a continuous convex panel, *s*, substantially as set forth.

15. 7. The design consisting of a sewing-ma-

chine arm mounted on a bed-plate and having the configuration substantially as set forth.

8. The design consisting of a sewing-ma- 20
chine bed-plate combined with a sewing-ma-
chine arm, both having the configuration sub-
stantially as shown and described.

In testimony whereof we affix our signatures in presence of two witnesses.
